UNITED STATES PATENT OFFICE

2,296,680

AIR CONDITIONING APPARATUS

David W. McLenegan, Caldwell, N. J., assignor to
General Electric Company, a corporation of New
York

Application November 29, 1941, Serial No. 421,069

7 Claims. (Cl. 62—6)

My invention relates to air conditioning apparatus and particularly to such apparatus which is provided with a closed housing for the motor-compressor unit.

It is sometimes desirable to construct air conditioning apparatus so that it includes two or more units comprising the several portions of the system each enclosed in a suitable casing which presents a pleasing appearance and minimizes noise. The casings may, if desired, be located in different portions of a building. Such apparatus frequently employs a motor-compressor unit completely enclosed by a housing and it is, therefore, necessary to provide some arrangement for removing the heat generated within the housing by operation of the motor and compressor. When there is an adequate supply of cooling water, the condenser may be enclosed within the housing together with a suitable coil for cooling the air in the housing, cooling water being circulated both through the condenser and through the coil. In many localities, however, it is desirable to employ evaporative condensers which cannot readily be enclosed within the housing and some additional arrangement must be provided for removing heat generated within the housing.

It is an object of my invention to provide an air conditioning apparatus including a compression type refrigerating machine having a motor and compressor arranged in a closed housing and an improved arrangement for removing heat generated by the apparatus within the housing.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a sectional elevation view of an air conditioner embodying my invention and Fig. 2 is a view of a portion of the apparatus shown in Fig. 1 illustrating a modified form of my invention.

Briefly, the apparatus shown in the drawing comprises a casing divided into upper and lower compartments, the upper compartment containing a refrigerant evaporator and a fan or blower for circulating air over the evaporator and into the space to be conditioned, and the lower compartment comprising a closed housing containing the compressor and its driving motor. The condenser is arranged externally of the casing

and is of the evaporative type comprising a condenser coil and a water spray and a fan for circulating air over the sprayed condenser surface. In order to remove the heat generated by the motor and compressor within the housing, a refrigerant coil is connected in the refrigerant circuit of the refrigerating machine between the evaporator and the compressor and air is circulated over the coil within the housing. In order to maintain the temperature of the air in the housing below a predetermined value, a temperature control is provided to modify the operation of the thermostatic expansion valve which controls the admission of refrigerant to the evaporator. This arrangement thus employs a portion of the refrigerating capacity of the machine for removing heat from the motor compressor housing.

Referring now to the drawing, in Fig. 1 I have shown an air conditioning unit comprising an upper casing 10 and a lower housing or casing 11. The upper casing is provided with an air inlet 12 and an outlet grille 13 and a blower 14 driven by an electric motor 15. The blower is arranged to draw air into the casing through the inlet 12 and over the surface of a finned coil evaporator 16 and thence out through the grille 13 into the room to be conditioned. The lower casing 11 forms with the bottom wall of the upper casing 10 a closed housing containing a refrigerant compressor 17 driven by a motor 18. The evaporator 16 and compressor 17 are connected in a closed refrigerant circuit including a condenser 19 and a liquid receiver 20. The condenser 19 is of the evaporative type and is arranged in a cooling tower or casing 21 through which air is circulated by operation of a blower 22. In order to spray water over the surface of the condenser 19 and provide evaporative cooling, the casing 21 is formed so that the lower portion thereof constitutes a sump within which a body of water 23 is maintained, make-up water being admitted to the casing from a supply line 24 under control of a valve 25 actuated by a float 26. Water from the casing 21 is circulated by a pump 27 and sprayed over the surface of the condenser 19 by a spray head 28 providing a plurality of sprays 29.

During the operation of the refrigerating machine, refrigerant is compressed by the compressor 17 and delivered through a connection 30 to the condenser 19 where the refrigerant is cooled and liquefied, the liquid refrigerant being delivered to the receiver 20. From the receiver 20 the liquid refrigerant flows to the evaporator 16

under control of a thermostatic expansion valve 31 having a temperature responsive element or thermal bulb 33 connected in heat exchange with the evaporator on the outlet side thereof so that the temperature of the bulb depends upon the temperature of the refrigerant withdrawn from the evaporator. The refrigerant vaporized in the evaporator 16 is returned to the compressor through a suction line 34.

In order to cool the air within the housing 11, I provide a cooling coil or evaporator element 35 connected in the refrigerant circuit of the refrigerating machine between the evaporator 16 and the compressor 17, and the cooling capacity of the refrigerant withdrawn from the evaporator 16 through the suction line 34 is therefore available to cool air within the housing 11 and constitutes the sole effective cooling capacity available for maintaining the temperature of the air below its predetermined desired maximum temperature. The air in the housing is circulated over the coil 35 by operation of a fan 36 driven by the motor 18.

Under certain load conditions it may happen that the setting of the thermostatic expansion valve 31 for normal operation will be such that insufficient cooling capacity remains in the refrigerant supplied to the coil 35. In order to assure sufficient cooling capacity to remove the heat generated by the motor and compressor within the housing 11, I provide an electric heating element 37 arranged to supply heat to the bulb 33 and control the energization of the heater by a thermostat comprising a spirally coiled bimetallic strip 38 arranged in the circuit of the heater 37 in series with the heater across supply lines 39 and 40 and arranged to vary the portion of a resistor 41 which shall be in series with the heater. The thermostatic expansion valve 31 is of the type commonly employed to control the amount of superheat of the vaporized refrigerant withdrawn from an evaporator, and the bulb 33 actuates an element of the valve so that the valve tends to open upon a rise in temperature of the bulb. It follows that by applying heat artificially to the evaporator 16 it is possible to open the valve 31 more than is necessary to supply the refrigerant required by the evaporator 16, and thereby the excess refrigerant is supplied to the coil 35. Under normal conditions of operation the refrigerant supplied to the coil 35 will be saturated or nearly saturated vaporized refrigerant. However, under extreme conditions of operation some liquid refrigerant may be supplied to the coil 35.

During the operation of the refrigerating apparatus, should the temperature of the air within the housing 11 rise, the bimetallic element 38 will move in a counterclockwise direction and reduce the amount of resistance in the circuit of the heater 37, and thereby increase the current flowing through the heater and raise the temperature of the bulb 33. This supplies an increased amount of cold or vaporizable refrigerant to the coil 35 and thereby reduces the temperature of the air in the compartment 11. The thermostat 38 will therefore operate to maintain the temperature of the air in the motor compressor housing below a predetermined value.

In some installations it may be desirable to arrange the housing 11 and the casing 10 in different parts of a building, and for this purpose the refrigerant connections may be opened by disconnecting pipe unions 42 and 43 in the liquid and suction lines, respectively, of the refrigerant

circuit so that sufficient refrigerant piping to extend the circuit and allow separation of the two units may be provided. The compartment 11 as shown is maintained closed by the bottom wall 5 of the casing 10. Obviously when the two casings are separated, a plate or closure corresponding to the bottom wall of the casing 10 is secured in place over the top of the casing 11.

In some installations adequate cooling of the housing 11 may be obtained by securing the bulb 33 of the thermostatic expansion valve 31 to be responsive to the temperature of the refrigerant withdrawn from the coil 35 as shown in Fig. 2. This arrangement maintains substantially constant the amount of superheat in the vaporized refrigerant withdrawn from the coil 35 and assures a sufficient cooling capacity for the coil 35. For some settings of the thermostatic expansion valve it may happen that after a long idle period 20 of the compressor there will not be sufficient heat available in the machinery compartment to cause the thermal bulb 33 to open the expansion valve. In such cases it is desirable to provide a heater 44 similar to the heater 37, and a thermostat 45 and variable resistor 46 for controlling the energization of the heater 44. The thermostat 45 is constructed so that on a fall in temperature in the machinery compartment it will reduce the portion of the resistor 46 in the circuit 30 and increase the energization of the coil 44 thereby supplying heat to the valve 33. Heat is thus available for opening the thermostatic expansion valve, even though the temperature of the machinery compartment has not risen to a value 35 sufficiently high to supply the heat. As the temperature of the compartment rises more resistance will be placed in the circuit and the energy supplied to the heater 44 will be reduced. With this arrangement the evaporator will operate at substantially full capacity very shortly after the condensing unit has been started.

During the operation of either of the systems illustrated, cooling capacity for reducing the temperature of the air in the machinery compartment is provided at all times without the necessity of arranging additional cooling apparatus such as water coils within the machinery compartment, and the apparatus is therefore readily adaptable for use with a remotely located condenser.

While I have shown my invention in connection with an air conditioner, other applications will readily be apparent to those skilled in the art. I do not, therefore, desire my invention to be limited to the particular constructions shown and described, and I intend in the accompanying claims to cover all modifications within the spirit and scope of my invention.

What I claim as new and desire to secure by Letters Patent of the United States, is:

1. A refrigerating system including a compressor and a condenser and an evaporator connected in a closed refrigerant circuit, a closed housing surrounding said compressor, means for circulating air within said housing and over said compressor, means including a refrigerant element arranged in said housing and connected in the refrigerant circuit of said system between said evaporator and said compressor for cooling the air circulated in said housing to remove heat produced by the operation of said compressor, and temperature responsive means arranged to control the admission of refrigerant to said evaporator for maintaining the temperature of the air circulated over said compressor below a predetermined value.

2. A refrigerating system including a compressor and a condenser and an evaporator connected in a closed refrigerant circuit, a closed housing surrounding said compressor, means for circulating air within said housing and over said compressor, means including a refrigerant coil arranged in said housing and connected in the refrigerant circuit of said system between said evaporator and said compressor for cooling the air circulated in said housing to remove heat produced by operation of said compressor, and a thermostatic expansion valve arranged to control the admission of refrigerant to said evaporator and having its thermal element secured in heat exchange relation with said refrigerant coil adjacent the outlet thereof for controlling the admission of refrigerant to said evaporator.

3. A refrigerating system including a compressor and a condenser and an evaporator connected in a closed refrigerant circuit, a closed housing surrounding said compressor, means for circulating air within said housing and over said compressor, means including a refrigerant element arranged in said housing and connected in the refrigerant circuit of said system between said evaporator and said compressor for cooling the air circulated in said housing to remove heat produced by the operation of said compressor, a thermostatic expansion valve arranged to control the admission of refrigerant to said evaporator and having its thermal element secured in heat exchange relation with said evaporator on the outlet side thereof, and means responsive to the temperature of the air in said housing for supplying heat to said thermal element to modify the operation of said expansion valve and to maintain the temperature of the air in said housing below a predetermined value.

4. A refrigerating system including a compressor and a condenser and an evaporator connected in a closed refrigerant circuit, a closed housing surrounding said compressor, means for circulating air within said housing and over said compressor, means including a refrigerant element arranged in said housing and connected in the refrigerant circuit of said system between said evaporator and said compressor for cooling the air circulated in said housing to remove heat produced by the operation of said compressor, a thermostatic expansion valve arranged to control the admission of refrigerant to said evaporator and having its thermal element secured in heat exchange relation with said evaporator on the outlet side thereof, an electric heating element for supplying heat to said thermal element, and means responsive to the temperature of the air in said housing for controlling the energization of said heating element to modify the operation of said expansion valve for maintaining the temperature of the air in said housing below a predetermined value.

5. Air conditioning apparatus including a casing and means for circulating air therethrough, a refrigerating machine including a compressor and a condenser and an evaporator arranged in a closed refrigerant circuit, said evaporator being arranged in said casing to cool the air circulated therethrough, means for cooling said condenser, a closed housing surrounding said compressor, means for circulating air within said housing, means including a refrigerant element arranged in said housing and connected in the refrigerant circuit of said refrigerating machine between said evaporator and said compressor for

cooling the air circulated in said housing to remove heat produced by the operation of said compressor, a thermostatic expansion valve for controlling the admission of refrigerant to said evaporator, said valve including a temperature responsive element secured in heat exchange relation with said evaporator on the outlet side thereof, a heater for supplying heat to said temperature responsive element and means responsive to the temperature of the air in said housing for varying the amount of heat supplied by said heater to modify the operation of said expansion valve for maintaining the temperature of the air in said housing below a predetermined value.

15 6. Air conditioning apparatus including a casing having an inlet and an outlet for the circulation of air therethrough, a refrigerating machine including a compressor and a condenser and an evaporator connected in a closed refrigerant circuit, said evaporator being arranged in said casing, means for circulating air through said casing from said inlet to said outlet to cool the air, means providing a closed housing surrounding said compressor, means for circulating air within said closed housing, said condenser being arranged externally of said housing, means for cooling said condenser, means including a thermostatic expansion valve having a thermal bulb arranged to be responsive to the temperature of the refrigerant withdrawn from said evaporator for controlling the admission of refrigerant to said evaporator, a refrigerant coil connected in the refrigerant circuit of said refrigerating machine between said evaporator and said compressor for cooling the air circulated within said housing, an electric heater for supplying heat to said thermal bulb, and thermostatic means dependent upon the temperature of the air within said housing for varying the energization of said heater to vary the supply of refrigerant to said refrigerant coil and to maintain the temperature of the air within said closed housing below a predetermined value.

40 7. Air conditioning apparatus including a casing having an inlet and an outlet for the circulation of air therethrough, a refrigerating machine including a compressor and a condenser and an evaporator connected in a closed refrigerant circuit, said evaporator being arranged in said casing, means for circulating air through said casing from said inlet to said outlet to cool the air, means providing a closed housing surrounding said compressor, means for circulating air within said closed housing, said condenser being arranged externally of said housing, means for cooling said condenser, a refrigerant coil connected in the refrigerant circuit of said refrigerating machine between said evaporator and said compressor for cooling the air circulated within said housing, means including a thermostatic expansion valve having a thermal bulb arranged to be responsive to the temperature of refrigerant withdrawn from said refrigerant coil for controlling the flow of refrigerant to said evaporator, an electric heater for supplying heat to said thermal bulb, and thermostatic means dependent upon the temperature of the air within said housing for increasing the energization of said heater upon a fall of the temperature of the air within said housing below a predetermined value.

DAVID W. MCLENEGAN.
